MULTIBAND PORTABLE RADIO

Paul J. Klucznik, Manlius, N.Y., assignor to
General Electric Company

Filed Jan. 12, 1973, Ser. No. 322,934

Term of patent 14 years

Int. Cl. D14—01

U.S. Cl. D56—4 B

FIG.1.

FIG.2.

FIG.3.

FIG.4.

FIG.5.

FIG.6.

FIG. 1 is a front elevational view of a multiband portable radio showing my new design.

FIG. 2 is a bottom plan view;

FIG. 3 is a top plan view;

FIG. 4 is a rear elevational view;

FIG. 5 is a right side elevational view; and

FIG. 6 is a left side elevational view.

I claim:

The ornamental design for a multiband portable radio, as shown.
